UNITED STATES PATENT OFFICE

HARRY H. WOLFE AND HARRY L. MYERS, OF TOLEDO, OHIO, ASSIGNEES TO THE AMERICAN FLOOR SURFACING MACHINE COMPANY, OF TOLEDO, OHIO

EDGING MACHINE

Application filed December 17, 1927. Serial No. 240,837.

This invention relates to a new type of floor surfacing machine to be commercially known as an edging machine.

In finishing around the marginal edge 5 portions of a floor, the work is usually accomplished with a small hand tool. This class of work is commonly referred to in the trade as "hand jerking."

Having noted the inconvenience of such 10 work and the laborious tasks encountered with the hand scraping tools on stair treads, doorways, small closets, and the like, we have developed a comparatively small portable machine which overcomes the innumerable objections known to the trade.

Briefly stated, the improved edging machine comprises a supporting base in the form of an especially designed metallic casting having a central elongated gear casting, on opposite sides of which are overhanging top flanges defining open side compartments for accommodating abrasive belts. There is a pair of these compartments in the present machine, and they are 20 constructed to contain a series of belt guiding and retention devices over which endless belts are trained in a manner to act on the floor adjacent the customary mop boards.

30 An appropriate prime mover is mounted on the base and has driving connection with the belts and also serves to operate the fan of a dust collecting device which is employed in association with the dust. There are operating handles properly located and an especially prepared truck on which the rear end of the base is fulcrumed.

Particularly, do we aim to produce an 40 especially constructed machine for edging work, which is capable of fulfilling the requirements of a machine of this class, one which is exceptionally efficient in performance, is smooth, quiet, and dependable, in operation, economical, practicable, a mechanical achievement beyond similarly constructed machines, and characterized by the presence of prominent and indispensable structural features.

50 A primary feature of construction is the dual arrangement of endless abrasive belts,

arranged in spaced parallelism in the open side compartments on opposite sides of the supporting base. The distinction to be noted about these belts, is that they are trained in a somewhat triangular manner 55 over a series of guide and retention devices, the lower one of which serves to yieldably press a comparatively small portion of the belt into firm surfacing contact with the floor.

An equally important structural distinction is a resilient pressure producing shoe, a detail employed in association with each belt and the means which maintains the active portion of the belt in contact with 60 the floor. The shoe has numerous advantages which will be made more evident as the description proceeds.

A further distinction, worthy of note, is 65 a novel belt tensioning means employed in association with each belt, and individualized by an arrangement of details capable of causing the belt to cling to a power pulley by exerting a longitudinal elastic stress upon the belt, and simultaneously twisting the belt transversely of its direction of movement.

The belt tensioning means has the additional advantage of providing a structure 70 which serves to release the belt to facilitate removal and replacement of the belt, and a notable feature in this connection is a manually operable lever which is active upon the belt tensioning means to permit it to be moved to a position for releasing and permitting ready removal of the belt.

Moreover, we propose an edging machine 75 of this class which is provided on its forward portion with rigid hand gripping means, and on its rear side with a swingably mounted operating handle, cooperating with a hand gripping means to aid in the use of the machine in small closets, and other similar places difficult of access.

Then too, we aim to increase the efficiency 80 of the structure by the addition of a small wheeled truck on whose central portion, the rear end portion of the base is rockably 85 fulcrumed to permit self leveling and to 90 95 100

bromote positive handling and easy manipulation.

The foregoing are the outstanding structural features which serve to characterize the new entity, and the advantages derived from their use, will be evident, as the description goes on.

In the drawings:—

Fig. 1 is a side elevational view, on a slightly reduced scale, showing an edging machine, as constructed in accordance with this invention, and indicating the approximate manner in which it is used.

Fig. 2 is an enlarged side view in section and elevation, showing the internal mechanism and other associated details.

Fig. 3 is a rear elevational view showing the special relationship of the fulcrumed truck.

Fig. 4 is a front end elevational view with one portion broken away, to expose the belt tensioning and releasing means.

Fig. 5 is an enlarged vertical section thru the lower portion of the machine, showing the belt guiding bracket, and a portion of the gear casing.

Fig. 6 is a perspective view one of the belt guiding brackets.

Fig. 7 is an enlarged detail view showing the manner in which this bracket cooperates with one edge of the abrasive belt.

Fig. 8 is an enlarged perspective detail view with the belt tensioning means removed from the body of the machine.

Fig. 9 is a perspective view of a part hereinafter referred to in the detailed description as a presser foot.

Considering now the specific construction of the various details of the invention, it will be observed that the reference character 10 designates generally what is broadly defined as a supporting base. This base comprises a single metallic casting having a central horizontal top portion construction for reception of a small vertical electric motor 11.

The front wall curves gradually downwardly assuming the configuration shown in Fig. 2, being provided with a vertical slot 12, and having its bottom edge terminating in spaced relation from the floor. Bolted or otherwise suitably fastened to this front wall is an appropriate buffer 13. The opposite rear end portion depends at a substantial right angle to the top portion and carries a removable housing 14 for a rotary suction fan 15, (see Fig. 2).

This wall is provided with a bearing 16, and a forwardly and downwardly inclined branch coupling 17 communicating with the fan housing. Formed centrally on the under side of the casting is a compartment defined by spaced walls cooperating in providing a gear casing. Extending down to this casing as shown in Fig. 2 is the motor

shaft, carrying a gear 18 below which is a beveled pinion 19. The beveled pinion 19 is in mesh with the beveled gear 20, on a horizontal power shaft 21 (see Fig. 5).

The gear 18 is meshed with a small pinion 22 on a vertical shaft 23, suitably journaled in appropriate bearings. Motion is transmitted from the shaft 23 to a complementary right angularly disposed shaft 24 through the medium of the intermeshing gears 25. Incidentally, the shaft 24 carries the aforesaid fan 15. With this arrangement, motion is imparted to the driving pulleys 26 on the ends of the shaft 21, and to the suction fan of the dust collecting device.

In connection with the latter, it might be stated that the reference numeral 27 designates generally, a unit (see Fig. 2), which is fastened on the branch 17, and includes intake arms 28 whose intake ends are located toward the front and in spaced relation with respect to each other. While considering the construction of the casting, we desire to point out further that the same includes a shelf-like extension 29 constituting a mounting for the handle 30. The handle includes a special metallic fitting 31, having a fork, with curved arms 32 which are pivotally mounted on the shelf to permit the handle to be swung from a rearwardly inclined position to a vertical upstanding position. In addition, this fitting includes a pair of relatively short centrally located arms 33 having arcuate slotted portions 34 which engage about a pin 35 to limit the forward swinging of the handle, and to stop it in a vertical upstanding position, as shown in Fig. 2.

The reason for having structures permitting the two positions of the handle, will become more readily apparent from the following description.

Also forming a part of the base is a depending web 36 underneath of the aforesaid suction branch 17, (see Fig. 2), this being equipped with a horizontal bearing 37. While considering these details, it is obvious that the purpose of the portions 36 and 37 is to provide a means for attaching a small truck 38 to the machine. The construction of this truck is plainly evident as shown in Fig. 3. It embodies an axle 39 having upturned ends equipped with bearings in which the axles of the small wheels 40 are mounted.

This axle is fulcrumed in the bearing 37 through the medium of a rocking and pivot pin 38a. At longitudinally spaced points, are integral outstanding screw threaded lugs 41, each carrying an adjusting and a stop screw 42. The stem of the screw is threaded upwardly thru the lug and carries a lock nut 43. That portion of the stem extending above the lug is encircled with a coiled spring 44, having its lower end engaged with

the lug, and its upper end pressing against a complementary abutment 45.

In connection with this truck construction, attention is particularly invited to Fig. 3, wherein it will be seen that the central fulcrum of the truck horizontal axis permits rocking of the truck in two directions. The rocking movement, however, can be regulated by adjustment of the stop screws. The 10 rocking action is ordinarily resilient because of the presence of the spring interposed between the truck axle and the body of the machine. While considering this figure, attention is invited to a side connection 46, 15 leading from the fan housing.

This connection is intended to accommodate a suitable swivelly mounted conduit 47, which leads to a dust collecting bag (not shown). In this instance, it might be necessary to say that in the actual machine, there is a dust collecting bag provided so that the dust from the abrasive action can be collected in the bag and disposed in any convenient manner.

25 As is apparent from Figs. 4 and 5, the central top portion of the casting is such in construction, as to provide outstanding flange portions which overhang the pulleys. 26. In fact, these flanges are such, that they 30 define open side compartments, for accommodating each abrasive endless belt 48 (see Fig. 1). From this figure, it will be noted that each belt is trained over a set of guide and retention devices, including the pulleys, 35 in such a way that the belt assumes a somewhat triangular form.

Only a small portion of the lower corner of the triangle is pressed into engagement with the floor. One of the devices over 40 which the belt is trained in each instance, comprises the tensioning means, as well as the means for releasing the belt to allow exchanging belts.

The particular construction of this device 45 is highly important, particularly because of the double function that it has. The device under consideration is detailed in Fig. 8. Reference being had to this figure, it will be seen that an essential part comprises a 50 yoke 49, having the curvature represented. The yoke includes a bearing 50 at its bottom, rockably mounted on a relatively stationary journal pin 51. The yoke embodies a web 52 at the upper end of the arms of which 55 are bearings 53, disposed at right angles to the bearing 50. Also one arm, carries an outstanding shoulder forming flange 54, whose function will be clear later.

Moreover, the numeral 55 designates an 60 abutment. This yoke is, obviously, swingable in a direction longitudinally of the abrasive belts. Mounted on the yoke is a pulley bracket, generally designated at 56.

This embodies a curved arm portion 57 65 carrying a set screw 58, engaging the abut-

ment 55. In addition, it is formed in its upper end with a bearing 59 rockable on an appropriate journal pin in the bearing 53. It includes an upstanding part 60, carrying a right angularly disposed pintle 61 on which a pulley 62 is rotatably mounted 70 for idling motion.

In connection with this bracket, we would also mention a plate-like portion 63 having a curved recess in its bottom, receiving the head 64 on the upper end of a pin 65. This pin extends down through a hollow boss 66 on the horizontal arm of a spring adjusting bracket 67. The bracket 67 is of right angular form, and is held in place by the turning bolt 68. The bracket can be turned about this bolt and set in any position to vary the vertical position of the pin 65.

Incidentally, a coiled spring 69 surrounds the pin and the boss, and bears against the bracket at its lower end and against the head 64 at its upper end. The spring pressed pin is so located with respect to the curved yoke 49, that it rocks the yoke in a direction from right to left around the pivot pin 51, 90 thus maintaining the resilient pressure upon the idling pulley 62, and tensioning the belt 48.

Attention is now invited to the reference numeral 70, designating a substantially 95 U-shaped member, whose right portion 71 forms a part of a clamp for a resilient shoe 72. The shoe comprises a resilient plate slit to provide pliable fingers 73 whose free ends are upturned, the opposite end of the plate 100 being clamped between the part 70 and a removable retaining bar 74. This U-shaped part 70 or clamp, has its arm portion provided with bearings 75 and 76 which are in alinement with the aforesaid bearing 50, as 105 shown in Fig. 8, and which slip over the same journal pins 51.

The bearing 76 is provided with an outstanding lug 77 located between the adjusting and retaining screws 78 on the stationary 110 ears 79 carried by the body of the machine. With this arrangement, it is obvious that the U-shaped clamp 70 can be adjusted through the medium of the screws 78, thereby moving the shoe 72 up or down to 115 effect angular adjustment of same.

From Fig. 1, it is evident that the shoe in each instance, is located so that the upturned ends of the fingers is substantially beneath the aforesaid rubber bumper 13. 120 With this arrangement, the abrasive surfaces of the belts can be brought close to the mop board 80, as is shown in Fig. 1.

Attention is invited now to Fig. 9, which shows a specially designed presser foot 81 125 which is clamped upon a rock shaft 82 on which an operating lever 83 is also mounted. This lever 83 extends up through the aforesaid slot 12 and is provided with a hand grip. The pressure foot 81 bears against 130

the shoulder 54 (see Fig. 8, and Fig. 2). Obviously, by pulling forwardly and downwardly on the lever 83, the presser foot 81 will be moved rearwardly, exerting pressure upon the yoke 49 and rocking this yoke upon its pivot 50 and 51 and permitting the pulley 62 to move toward the stationary drive pulley 26, thereby loosening the belt and permitting it to be removed and replaced.

The operation of the combined belt tensioning means and releasing means is therefore obviously seen. It may be conveniently stated again, that the stress of the aforesaid spring 69, is such as to exert an upward and forward thrust upon the peculiarly curved yoke. Since this yoke carries the idling pulley, it is obvious that this yielding pressure is exerted upon the inside of the abrasive belt which is trained thereover.

To overcome the tension of this spring, whenever it is desired to change the belt, the lever 83 is grasped and pulled forwardly and downwardly, and acting through the medium of the rock shaft, and the presser foot 81 carried thereon, the yoke 49 is swung rearwardly upon its pivot moving the idling pulley away from the belt in such a manner as to permit it to be easily removed and replaced. If desired, suitable retaining means for the lever, (not shown), can be provided in practice to hold the idling pulley in this swung-down position to facilitate exchanging of belts.

It is to be noted that the triangular shape of the belt, follows the general outline of the walls of the base. Thus the machine is allowed to approach the mop board 80, at a direct right angle as shown in Fig. 1, without interference from any projections or obstructions carried by the machine. Moreover, the rearward inclination, of the belts at this time prevents them from striking or coming into contact with the mop boards. Consequently, the structure is especially adapted for edging work.

From the foregoing description and drawings, it is obvious that we have evolved and produced an edging machine of a comparatively small portable type, wherein the base or body has its rear end portion rockably mounted on a fulcrum with comparatively small portions of the abrasive sides of the two belts, pressed down firmly on the floor at the front of the machine. These belts are in spaced parallel relationship, and when trained over the guiding and retention devices, they assume the triangular shape shown. The compartments in which they are located are completely open to facilitate exchanging and to expedite regulation.

As the belt operates, the dirt and dust is sucked in through the arms of the dust collection device, an indispensable feature in a

machine of this class. In a machine of this kind, particularly of the light weight portable type, it can be appreciated how difficult it is to maintain the abrasive belts properly trained over the guiding and operating means. Naturally, considerable resistance is set up during the operation of the belt, and this has a tendency to accidentally displace the belt. Thus in practice, the driving pulleys 26 at the ends of the shaft 21, are of a straight face rubber covered type, to insure proper driving action.

By the cooperation of the headed spring pressed pins 65 (Fig. 8), and the idling pulley 62, this pulley is able to maintain a longitudinal thrust upon its belt, thus maintaining the belt stretched in a taut manner. This avoids, longitudinal displacement of the belt, by picking up excessive slack. However, it has been noted, that this longitudinal pressure alone, is not sufficient to hold the belt in place. Therefore, it becomes necessary to virtually twist the belt transversely of its direction of movement, and this is accomplished by having the idling pulley 62 mounted on a separate and individually adjustable bracket 56, wherein the axis of swinging motion of this bracket is at right angles to the axial motion of the yoke 49. In other words, the yoke 49 is swingable longitudinally of the belt and held forwardly by the spring-pressed pin 65, while the bracket 56 swings in a direction at right angles, or transversely of the abrasive belts.

However, the adjustment of action of the belt is not restricted to the cooperation of these parts 49 and 56, since the shoe 72 is individually adjustable by the screw 78 operating through the ears 79 and connecting upon the lugs 77. Then too, the presence of the resilient fingers on the shoes renders the same adaptable to irregularity in the surface traversed.

At this time attention is invited to Figs. 5, 6, and 7, wherein it will be observed that the reference character 85 designates generally, a bracket. There are two of these brackets provided, one for each belt. Each bracket comprises a strip of metal 86 having an elongated slot at one end portion, and having its intermediate portion 87 twisted. The free ends terminate in an especially shaped head 88. These brackets are adjustably bolted on the bottom of the gear casing as shown in Fig. 5, and extend out at right angles, so that the heads 88 are in the path of movement of the belt and in fact, engage the edge of the belt in each instance. These constitute guides and stop members for limiting the inward or transverse slippage of the belts.

Obviously, owing to the abrasive material on the belts, they would ordinarily soon wear away the metal of the head 88. How-

ever, by shaping the head as shown in Fig. 7, the edge of the belt is turned outwardly, as shown at 89 in Fig. 7, thereby overcoming undue wear on the head.

5 One of the principal advantages of this improved edging machine is that it is characterized by a base or body of convenient construction, which includes the means for supporting a prime mover in the form of a vertical motor, being further constructed to provide a housing or a casing for the gearing and driving mechanism, both for the belt and for the dust collecting fan, and being further individualized by the presence of 10 the two open sided compartments in which the belts run.

15 A further advantage is based upon the utilization of the bumper on the properly shaped front wall, which is so located as to come into engagement with the mop board, and to limit the movement of the machine in this manner. However, due to the location of the resilient shoes beneath this bumper, it is obvious that the edging operation 20 can be carried on within about one-quarter of an inch of the mop board. Incidentally, it is usually advisable to remove the molding strip or shoe so that this close up edging action can take place. Then when 25 the shoe is replaced, the small portion which was not surfaced, will be substantially unnoticeable.

Not only is the spaced parallel dual belting arrangement thought advantageous in 30 this particular machine, but novelty is predicated upon the three-point bearing action which is accomplished with the structure. In other words, the forward points 35 constitute the transmission of the weight on the two resilient adjustable shoes at the front. A central rear portion of the machine, however, is suspended from the centralized fulcrum of the truck. However, the truck wheels are constantly on the floor 40 and within this arrangement, it is possible to shift the weight of the motor of the machine from either one side to the other, to bring about an equalizing action on the belts.

Sometimes, one belt will drag and the 45 other belt will slide, setting up somewhat of an undesirable differential action which will decrease the efficiency. Under ordinary circumstances, however, the interpositioning of the springs between the fulcrumed truck and body permits a substantial self-leveling action and relieves the belts and forces them 50 to have substantially equal action. If the operator desires, however, he can, through the medium of the rigid handle, exert pressure on either one belt or the other by tilting the body of the machine in any direction desired. This is a highly important feature, 55 to be remembered.

60 Likewise, the resilient adjustable shoe is very important, because of the swinging 65

nature, because of the fact that the abrading belt will follow substantially all irregularities of the floor. The action of the spring is to be somewhat individual in its effect. The peculiar curvature of the bottom of this shoe is to be noticed, and the adjustable mounting of the shoe is of great importance, as different pressures are necessary on different textures of flooring.

70 It is to be further added that the shifting of the load of the machine has a great deal to do with the belt alinement, as the contact of the abrading is increased, so is the tendency of the belt to run from their proper alinement. This however, is overcome by 75 the novel belt twisting and idler pulley adjusting means.

80 Further, in connection with the shoe, it is essential that the shoe be so constructed and made of such a material that the transmission of heat generated by friction as the belt passes over the shoe and floor be held to a minimum. In fact, the thin nature of the metal from which the shoe is 85 constructed, prevents the metal from absorbing too much heat, and permits the heat to radiate freely and rapidly. Thus it is not transmitted to the adjacent mechanism, and this is important.

90 A careful analysis of the description in the presence of the drawings, will enable the reader to recognize the importance and distinctions, and to appreciate the structural features, which adapt this machine particularly for edging floors. As the 100 method of use, operation, and advantages appear clear, a more lengthy description is thought and regarded unessential.

Having thus described our invention, 105 what we claim as new is:—

1. In an edging machine of the class described, a body comprising a longitudinally elongated gear casing provided with outwardly extending side flanges defining open-sided belt compartments, the forward side 110 of said body including an outwardly and downwardly inclining portion terminating in spaced relation to the floor, a horizontal bumper carried by the lower end portion thereof, adjustably mounted resilient shoes 115 supported in the forward and lower portions of said compartments, substantially beneath said bumper, a driving pulley located in each compartment, operating means for the pulley including a prime mover supported on said body, endless abrasive belts located in the compartments, and trained over the pulleys and shoes, an operating handle connected to the body, and dust collecting means including outwardly directed 120 branches having their intake ends located beneath the bottom flights of said abrasive belts, together with spring pressed belt tensioning means located in each compartment, 125 and cooperable with the complementary bear- 130

ings, and a manually operable means for acting upon the tensioning means for moving it in a direction to release the belts to facilitate replacement.

5 2. In an edging machine of the class described, a base having a belt compartment, a stationary operating pulley in the construction, a rigid journal pin in the compartment, a yoke mounted for longitudinally swinging 10 motion on said pin, an idler pulley disposed in a substantial horizontal line with said driving pulley, and movable with respect thereto, an idler pulley bracket, means swingably mounting said bracket on said 15 yoke, the axis of movement of the bracket being at right angles to the axis of said yoke, spring pressed means cooperable with the yoke for swinging it around its pivot in a direction longitudinally of said compartment, a shoe in said compartment, an endless belt trained over said idler pulley, operating pulley, and shoe, and confined in said compartment, a motor supported on said base, an operating connection between 20 the motor and driving pulley, and a handle connected with the base.

3. In an edging machine of the class described, a base provided with a belt compartment, an operating pulley in said compartment, a motor on the base, an operating connection between the motor and pulley, a handle connected to the base for manipulating the base, a shoe mounted in the compartment, a yoke swingably mounted in the compartment, the yoke being swingable in a direction longitudinally of the compartment, a bracket pivotally mounted on the yoke and swingable in a direction at right angles to the yoke, an adjusting screw carried by the bracket and engageable with the yoke, a spindle carried by the bracket, an idling pulley on the spindle, and adjustable spring means engaging the bracket for moving it in a forward and longitudinal direction in the compartment, a belt trained over the idler pulley, the driving pulley, and shoe.

4. In an edging machine of the class described, a base provided with a belt compartment, an operating pulley in said compartment, a motor on the base, an operating connection between the motor and pulley, a handle connected to the base for manipulating the base, a shoe mounted in the compartment, a yoke swingably mounted in the compartment, the yoke being swingable in a direction longitudinally of the compartment, a bracket pivotally mounted on the yoke and swingable in a direction at right angles to the yoke, an adjusting screw carried by the bracket and engageable with the yoke, a spindle, and adjustable spring means engaging the bracket for moving it in a forward and longitudinal direction in the compartment, a belt trained over the

idler pulley, the driving pulley and shoe, together with a guide bracket mounted on said base and having an enlarged curved head with which one edge of said belt has sliding contact, said head being constructed 70 to turn the belt edge outwardly.

5. In an edging machine of the class described, a base provided with a belt compartment, an operating pulley in said compartment, a motor on the base, an operating connection between the motor and pulley, a handle connected to the base for manipulating the base, a shoe mounted in the compartment, a yoke swingably mounted in the compartment, the yoke being swingable in a direction longitudinally of the compartment, a bracket pivotally mounted on the yoke and swingable in a direction at right angles to the yoke, an adjusting screw carried by the bracket and engageable with the yoke, a spindle, and adjustable spring means engaging the bracket for moving it in a forward and longitudinal direction in the compartment, a belt trained over the idler pulley, the driving pulley and shoe, together with a guide bracket mounted on said base and having an enlarged curved head with which one edge of said belt has sliding contact, said head being constructed to turn the belt edge outwardly, a rock shaft mounted on the base, a presser foot carried by the rock shaft and in engagement with the yoke for moving the yoke in a direction against the tension of the spring means, and an operating lever 100 mounted on the rock shaft.

6. A new product of manufacture for use in association with an edging machine of the class herein described, comprising, a guide bracket in the form of a flat metal strip provided at one end with an elongated slot, said strip being twisted intermediate its ends and terminating at its outer end in an enlarged head, said head having an arcuate belt engaging surface designed for turning 105 the edge of a belt outwardly to minimize wear on the head.

7. As a new product of manufacture, a belt tensioning device for use in association with an edging machine of the class described, comprising a substantially V-shaped yoke provided at its lower end with a bearing, provided intermediate its ends with an abutment, having the upper ends of its arms terminating in additional bearings disposed at right angles to the first named bearing, a shoulder forming flange carried by one of the arms of the yoke, an idler pulley bracket comprising an arcuate arm provided intermediate its ends with a bearing disposed between the second-named bearings and the upper ends of said yoke arms, a connecting pin between the bracket bearing and said last-named yoke bearing, a set screw carried by the lower end of said bracket arm 120 125 130

and engageable with said abutment, an up-standing part carried by the upper inner end of said bracket, and a spindle on said upper end together with an idler pulley mounted on said spindle, an additional bracket for adjustable mounting, a pin carried by said additional bracket, said pin having a head at its upper end engageable with the corresponding end of said spindle bracket, and a spring surrounding said pin, bearing at its lower end against the adjusting bracket and at its upper end against the head of said pin.

8. In a portable floor sanding machine adapted to rest on the floor or other surface that is being treated, two parallel transverse rollers, a stationary shoe extending forwardly below and in advance of the forward roller, the bottom of the shoe adjacent to the front end being approximately horizontal and the said end being of comparatively small vertical height, and an endless abrading belt embracing the rollers and the shoe, that part of the belt underlying the forward portion of the shoe serving as a support for the machine.

In testimony whereof we affix our signatures.
